(57) **CLAIM**

The ornamental design for a nerve stimulation device, as shown and described.

DESCRIPTION

FIG. 1 is a back view of the nerve stimulation device;
FIG. 2 is a front view of the nerve stimulation device;
FIG. 3 is a top view of the nerve stimulation device;
FIG. 4 is a bottom view of the nerve stimulation device;
FIG. 5 is a right side view of the nerve stimulation device;
FIG. 6 is a rear perspective view of the nerve stimulation device; and,

FIG. 7 is a front perspective view of the nerve stimulation device.

The broken line in the drawings represent portions of the nerve stimulation device and forms no part of the claimed design. The left side view (not shown) is a mirror image of the right side view.
